UNITED STATES PATENT OFFICE.

RENE D. GROVE, OF MIDDLETOWN, PENNSYLVANIA.

DESIGN FOR AN ANIMAL TOY.

Application filed May 14, 1927. Serial No. 21,989. Term of patent 7 years.

To all whom it may concern:

Be it known that I, RENE D. GROVE, a citizen of the United States of America, residing at Middletown, in the county of Dauphin and State of Pennsylvania, have invented a new, original, and ornamental Design for an Animal Toy, of which the following is a specification, reference being had to the accompanying drawing, forming part thereof.

The figure is a perspective view of an animal toy embodying my design.

I claim:

The ornamental design for an animal toy, as shown.

RENE D. GROVE.
